The ornamental design for an inhaler, as shown and described.

DESCRIPTION

FIG. 1 is a top, front and left side perspective view of a first embodiment of an inhaler, showing our new design;

FIG. 2 is a front view thereof;

FIG. 3 is a left side view thereof;

FIG. 4 is a rear view thereof;

FIG. 5 is a right side view thereof;

FIG. 6 is a top view thereof; and

FIG. 7 is a bottom view thereof;

FIG. 8 is a cross-sectional view along lines 8-8 of FIG. 3;

FIG. 9 is a top, front and left side perspective view of a second embodiment of an inhaler showing our new design;

FIG. 10 is a front view thereof;

FIG. 11 is a left side view thereof;

FIG. 12 is a rear view thereof;

FIG. 13 is a right side view thereof;

FIG. 14 is a top view thereof; and

FIG. 15 is a bottom view thereof; and,

FIG. 16 is a cross-sectional view along lines 16-16 of FIG. 11.

The features shown in broken lines depict portions of the inhaler that form no part of the claimed design. The dash-dot horizontal lines in FIGS. 8 and 16 show the boundaries of the cross-sectional views shown.
